L. E. FULTON

Des. 157,365

TELEPHONE SHELF

Filed Jan. 6, 1949

FIG. 2

INVENTOR.
LOUIS E. FULTON

L. E. Fulton
ATTORNEY

UNITED STATES PATENT OFFICE

157,365

TELEPHONE SHELF

Louis E. Fulton, Houston, Tex.

Application January 6, 1949, Serial No. 102

Term of patent 14 years

(Cl. D33—3)

To all whom it may concern:

Be it known that I, Louis E. Fulton, a citizen of the United States, residing at 2634 Persa Street, in Houston, county of Harris, and State of Texas, have invented a new, original, and ornamental Design for a Telephone Shelf, of which the following is a specification, reference being had to the accompanying drawings, forming part thereof.

Fig. 1 is a perspective view showing the general outline and appearance of the design of this invention.

Fig. 2 is a side elevational view of the invention; and

Fig. 3 is a front end elevational view of the invention.

I claim:

The ornamental design for a telephone shelf, as shown.

LOUIS E. FULTON.
